UNITED STATES PATENT OFFICE.

ERNEST STENGER AND NELSON R. LOVE, OF DENVER, COLORADO.

RAILWAY-TRACK CONSTRUCTION.

Application filed January 15, 1926. Serial No. 81,413.

Our invention relates to railway track construction, the improvements comprised therein being of particular value in the construction of street railway tracks in 5 paved streets or highways.

It is the primary objects of the present invention to provide durable and efficient cushioning means which permit of a limited yielding movement of the rails of a rail-way track in a vertical direction relative to a fixed and rigid supporting element, while maintaining the rails against horizontal dis-placement.

A further object of the invention is to 15 provide in addition to the above mentioned connecting means, cushions which will separate the rails of a track from the surrounding rigid paving material in which the track is partially imbedded and permit the 20 proper gauge and alignment to be maintained independently from the paving, and still another object is to provide a connection between the rails of the track and the ties to which they are attached, which is 25 subject to elastic deflection or deformation in a vertical direction to prevent the vibrations and shocks imparted to the rails by moving loads from being transmitted to the ties or the foundation on which they are 30 supported.

By the use of our invention a railway track may be laid in a paved area and so constructed as to have every advantage of the resiliency of a so-called open or unpaved 35 track which is supported by wooden ties laid in the ground or upon ballast.

The cushioning and resilient connecting means employed in our invention as briefly described hereinabove, lessen the noise and 40 vibration incident to the movement of the rolling stock along the railway, and absorb the shocks incident to the operation of the cars, so as to prevent them from being trans-mitted to the ties or to the structure on 45 which the ties are supported.

The load of the rolling stock, imposed on the rails, is also completely supported by the cushioning and resilient connecting means interposed between the rails and the ties and their supporting structure, so that 50 in addition to the advantages hereinbefore enumerated, the wear on both the rolling stock and the track-supporting structure is materially decreased.

Considering furthermore that the cushioning and supporting means of our invention operate to yieldingly support the rails at the proper elevation, while they also maintain the proper gauge between the rails and hold the rails in a vertical position 60 or at any desired inclination thereto, it will be evident that the invention is a decided advance in the art of street railway construction.

In the accompanying drawings, we have 65 illustrated different forms and arrangements of parts showing embodiments of our invention which adapt it for use under varying conditions, it being understood that all of said embodiments are within the scope and 70 spirit of the invention as set forth in the following description and defined in the hereunto appended claims.

In the drawings, in the several views of 75 which like parts are similarly designated,

Figure 1 represents a fragmentary plan view of our improved railway track,

Figure 2, a section along the line 2—2, Figure 1, showing the track in position relative to its foundation structure and the 80 paved area in which it is laid,

Figure 3 is a section taken on the line 3—3, Figure 1,

Figure 4, a section similar to that shown in Figure 1 illustrating a modified position 85 of the means by which the rails of the track are supported on the ties,

Figure 5, a fragmentary plan view of the construction shown in Figure 4,

Figure 6, a longitudinal section through 90 one of the rails of the construction illustrated in Figures 1 to 3, taken on the line 6—6, Figure 1,

Figure 7, a transverse section of the track, illustrating a modified construction of the 95 resilient means which support the rails upon the ties.

Figure 8, a fragmentary plan view of the form of the invention illustrated in Figure 7,

Figure 9, a transverse section of the track, showing the inclusion of cushioning means at the sides of the rails as is required on street or highways paved with a rigid substance such as stone block, brick or concrete, 105

Figure 10, a fragmentary horizontal sec-tion in the plane indicated by the line 10—10 in Figure 9,

Figure 11, a cross-section of the track in a vertical plane between the ties, as indicated by the line 11—11 in Figure 10,

Figure 12, a fragmentary plan view of 5 the track, illustrating the application of auxiliary supports for the rails between the ties;

Figure 13, a cross-section along the line 13—13 in Figure 12,

10 Figure 14, a cross-section through one of the rails of the railway track, showing a modification in the construction of the cushioning and supporting elements which are the main features of our invention,

15 Figure 15, a cross-section of the rail in the construction illustrated in Figure 14, taken in a vertical plane between the ties of the track,

20 Figure 16, a transverse section through one of the rails, showing another modification of the resilient supporting means,

Figure 17, a cross-section of the track, in which the resilient supporting means are formed as an integral part of the ties, and

25 Figure 18, a fragmentary section in the plane 18—18, Figure 17.

Referring to the figures of the drawings in their numerical order, the metal ties 5 of the construction illustrated in Figures 1, 2, 30 3 and 6, are supported in a foundation 6 of concrete or other similar rigid material, and the rails 7 are laid in a plastic paving substance 8, such as asphalt.

35 Cushions 9, composed of a plastic and elastic substance, such as asphalt or a mixture of asphalt and other materials, or any other durable and flexible material, are interposed between the rails along the entire length thereof, and the ties and foundation 40 upon which the rails are supported.

The cushions function in the operation of the railway to absorb the shocks and vibrations produced by movement of the cars along the track and to prevent the same 45 from being communicated to the foundation elements of the structure.

The rails of the track are furthermore supported on the ties by means of resilient connections in the form of metal Z-shaped 50 chairs, plates or brackets 10 which are fastened to the ties and to the rails by welding, bolts, rivets, clamps or other suitable means. The chairs or brackets, made of inherently 55 resilient metal, are subject to elastic deflection or deformation, and they permit of a yielding movement of the rails under loads without materially disturbing their gauge or vertical position or whatever inclination thereto which has been established. The deflection of the rails is not communicated to 60 surrounding paving owing to the flexible nature of the paving in the case of its being asphalt or that of the cushion interposed between the rails and the paving when 65 the latter is constructed of rigid material.

The form of the invention illustrated in Figures 4 and 5 differs from the first described form only in that the position of the metal brackets is reversed so that they are fastened to the ties between the rails instead 70 of at the outside of the same.

In the construction illustrated in Figures 7 and 8, the brackets or chairs 12 are of inverted U-shape and fastened to the ties at both ends and at opposite sides of the rails. 75

In Figures 9, 10 and 11 is illustrated a track laid entirely in a paving 13 of concrete, stone, brick or other rigid material.

In the use of concrete as shown in the drawings, the paving and the track foundation 80 6 may form a homogeneous mass. The rails are supported on elastic cushions 14 and resilient metal brackets 10 as before, but in order to provide for the yielding vertical movement of the rails, cushions 14 and 15 85 of elastic material are interposed between the rails along the entire length thereof, and the rigid paving material in which the rails are laid.

The side cushions may be made integral 90 parts of the cushions beneath the rails as best shown in Figure 11. It will be apparent that the cushions and supporting means will completely support the loads imposed 95 on the rails and will prevent of stress and shocks incident to the movement of the load being transmitted either to the ties, the track foundation or the surrounding roadway material.

In the form illustrated in Figures 14 and 100 15, the resilient brackets 16 which support the rails upon the ties, are provided with upwardly extending arms, so that they may be fastened to the webs of the rails, and the cushions 17, 18 and 19 beneath and at the 105 sides of the rails are made of wood.

In this construction or other similar constructions, the rails may be supported between the ties upon wooden blocks 20 as illustrated in Figures 12 and 13, in which case 110 clips 21 are spiked on the blocks to hold them in place by engagement with the feet of the rails.

In order to increase the resiliency of the support, cushions 22 of plastic material like 115 those employed in the other forms of the invention hereinbefore described may be interposed between the feet of the rails and the wooden blocks as illustrated at Figure 13.

In Figure 16 has been shown a resilient bracket 23 of Z-shaped form, fastened to the tie beneath the rail, and in Figures 17 and 18 the brackets 24 are made integrally with the ties 25 by cutting and bending upwardly 125 parts of the metal of which they are composed.

The ties are made of channel bars as shown in Figure 18, and the brackets are cut out of the upper flanges thereof and bent upwardly 130

to engage the feet of the rails to which they are fastened as before.

Having thus described our invention, what we claim and desire to secure by Letters Patent is:

1. In railway track construction, the combination with the rails and ties of a railway track, a foundation element, and a paving in which the rails are laid, of means of resilient material fastening the rails to the ties, resilient cushions supporting the rails on the foundation element, and resilient cushions between the sides of the ties and the paving.
- 10 2. In railway track construction, the combination with the rails and ties of a railway track, and a foundation element, of means of resilient material fastening the rails to the ties, and resilient means supporting the rails between the ties.
- 15 3. In railway track construction, the combination with the rails and ties of the railway track, and a foundation element, of vertically resilient means supporting the rails on the ties, means for supporting the rails on the foundation element between the ties, and resilient cushions between the rails and the last mentioned supporting means.
- 20 4. In railway track construction, the combination with the rails and ties of the railway track, and a foundation element, of resilient means supporting the rails on the

ties, and cushions supporting the rails between the ties.

5. In railway track construction, the combination with the rails and ties of a railway track, and a foundation element of resilient brackets supporting the rails on the ties, and cushions of plastic material supporting the rails on the foundation element between the ties.

6. In railway track construction, the combination with the rails and ties of a railway track, and a foundation element, of resilient brackets supporting the rails on the ties, and cushions of plastic material supporting the rails on the ties and on the foundation element between the ties.

7. In railway track construction, the combination with a foundation element and ties rigidly fixed in said element throughout their length, of continuous resilient cushions upon and between the ties, and rails upon the cushions.

8. In railway track construction, the combination with a foundation element and ties rigidly fixed in said element throughout their length, of resilient cushions upon the ties, rails on the cushions, and resilient means for fastening the rails to the ties.

In testimony whereof we have affixed our signatures.

ERNEST STENGER.
NELSON R. LOVE.
